(57) **CLAIM**

The ornamental design for a weighing device, as shown and described.

DESCRIPTION

FIG. 1 is a perspective view of a weighing device showing our new design;

FIG. 2 is a side view thereof;

FIG. 3 is a side view thereof;

FIG. 4 is a front view thereof;

FIG. 5 is a top view thereof; and,

FIG. 6 is a perspective view thereof.

The broken lines appearing in FIGS. 1-6 form no part of the claimed design.

1 Claim, 6 Drawing Sheets
